(57) **CLAIM**

The ornamental design for a pair of microphones as shown and described.

DESCRIPTION

FIG. 1 is a perspective view of a microphone of a pair of microphones showing our new design, the microphone is shown separately for ease of illustration;

FIG. 2 is a front view thereof;

FIG. 3 is a back view thereof;

FIG. 4 is a left view thereof;

FIG. 5 is a right view thereof;

FIG. 6 is an enlarged top view thereof;

FIG. 7 is an enlarged bottom view thereof;

FIG. 8 is an enlarged view of the encircled area 8 of FIG. 1; FIG. 9 is a perspective view of a microphone of a pair of microphones thereof, shown separately for ease of illustration;

FIG. 10 is a front view thereof;

FIG. 11 is a back view thereof;

FIG. 12 is a left view thereof;

FIG. 13 is a right view thereof;

FIG. 14 is an enlarged top view thereof;

FIG. 15 is an enlarged bottom view thereof;

FIG. 16 is an enlarged view of the encircled area 16 of FIG. 9;

FIG. 17 is a perspective view of a pair of microphones thereof;

FIG. 18 is a front view thereof;

FIG. 19 is a back view thereof;

FIG. 20 is a left view thereof;

FIG. 21 is a right view thereof;

FIG. 22 is a top view thereof; and,

FIG. 23 is a bottom view thereof.

The broken lines depict the use environment of the pair of microphones that do not form part of the claimed design. The dot-dash broken lines encircling portions of the microphone in FIGS. 1 and 9 and illustrated in the enlarged views of FIGS. 8 and 16 form no part of the claimed design.

1 Claim, 23 Drawing Sheets
